MATCH AND TEE PACKAGE

Andrew Lyle Linderman, Pittsburgh, Pa.

Application May 4, 1935, Serial No. 19,838

3 Claims. (Cl. 206—47)

This invention relates to containers for elongate and generally spindle-shaped articles, and finds practical application as a common container for matches and golf tees, to afford a package that 5 may conveniently be slipped into the pocket and that possesses the features of simplicity, cheapness, rigidity, and adaptability that are herein-after set forth. This application is in part a renewal of an application filed by me June 26, 1929; 10 Serial No. 373,711.

In the accompanying drawings Fig. I is a plan view of a sheet of stiff paper, or other suitable material, cut to form the blank from which the container of the invention is shaped; Fig. II shows 15 in perspective the partially shaped blank; Fig. III is a view in elevation and Fig. IV a view in transverse section (on the plane indicated at IV—IV, Fig. III) of a holding element for golf tees (tees are in the figures shown in place in this element) 20 that may be included in the make-up of the container. Fig. V is a view in front elevation of the completed package with a flap raised, to give access to the supply of contained golf tees; Fig. VI is a view in side elevation of the completed and 25 closed package; Figs. VII and VIII are views corresponding to Figs. I and VI and illustrating a modification in structure.

The sheet 1 of Fig. I—a sheet of suitable material, typically stiff tough paper—is so cut and 30 weakened along lines of bending (indicated by dotted lines) as to include duplicate rectangular panels 5 and 6, united at their edges along the line 4. Panel 5 is prolonged in terminal extensions 8 and 10, and panel 6 is prolonged in terminal extensions 7 and 9, and these extensions are at their bases weakened along transverse double parallel 35 lines, as indicated by dotted lines.

The weakening of the sheet along the dotted lines may be effected by creasing or by lines of 40 perforations, and, generally, in such particular manner as may be preferred and found convenient, to facilitate bending and to give precision to the place of bending.

The sheet 1 is bent along these lines of weakening. Along the line 4 it is bent in one direction from the plane of extent of the original sheet; along all the other lines (Figs. I—VI) it is bent 45 in opposite direction. In Fig. II the sheet is shown in course of bending along line 4, and along the lines at the bases of extensions 7 and 9; and in Fig. VI the completion of the bending is shown in the finished article. The panels 5 and 50 6 are brought face to face; and the opposite pairs 55 of extensions, 7—9 and 8—10, are bent to form

flaps that surround contained articles and that come to interengagement at their edges.

The panels 5 and 6 may be secured in face-to-face engagement, in any appropriated manner, as by gluing lightly along the otherwise free edges, 5 by means of an ordinary paper clip (17, Fig. V), or by a light staple. I prefer, however, to provide securing means that are fashioned from the sheet itself. Such preferred provision is illustrated in Figs. VII and VIII, and will hereinafter be more 10 particularly described. Since herein adaptation is found, to produce an organized whole of simplest form and cheapest fabrication, I shall claim it as involving substantive invention.

The holding element for golf tees, illustrated in 15 Figs. III and IV, is conveniently made of like paper stock with the container itself, bent to form a wedge-shaped cell 13, with perforate base. This cell is strengthened and partitioned internally by means of a corrugated sheet 15 to form 20 a succession of longitudinally extending compartments. The perforations in the base of this cell are aligned with the compartments, that the shanks of golf tees 14 may be inserted, and that a number of golf tees (in this instance four) may 25 so be removably secured and carried. This wedge-shaped cell 13 is, as shown in Figs. V and VI, secured at its narrower end by means of a staple 11 to the panel 6 beneath the inbent extension 9. The opposite extension 7 is bent to 30 form a cover over the cell 13 and its charge of golf tees. The staple 11 placed in the manner shown gives form and rigidity to this portion of the package, and yet leaves the edge of extension 9 sufficiently free to form a lip for retaining the 35 edge of the infolded extension 7 when slipped to place beneath it, in the position shown in Fig. VI.

Similarly as the cell for golf tees is secured beneath in-bent extension 9, a strip 12 of paper matches is secured at its continuous base to panel 40 5 and beneath in-bent extension 10; this second securing staple 11 cooperates to give rigidity as well as integrity to the package; and extension 8 when similarly bent in becomes the cover, over the charge of matches, and it similarly is retained 45 beneath the lip of the in-bent and secured extension 10. The exposed face of extension 10 may be coated, as is usual, with a match-striking composition.

The cell 13 and the strip of matches 12 will 50 be applied and secured by staples 11 before the sheet is bent along the line 4 and the panels brought together and secured in their ultimate face-to-face contact.

The pairs of extensions 7—9 and 8—10 are so 55

oppositely arranged with respect to the panel assembly 5-6 that the flaps formed by the extensions 7 and 8 open both from opposite sides and at opposite ends of the package, so that (with reference to Fig. VI) the golf tees are accessible from above and at the left, while the matches are accessible from below and at the right. This arrangement makes for the compactness and the rigidity of the package as a whole; and, since the size of the head of a tee is greater than that of a match, and the lines of bending are spaced in accommodation to that disparity, it is immediately manifest to the user of the package when he withdraws it from his pocket, both by the sense of touch and by sight, which end he should open to take a tee, which open to take a match.

In the modification illustrated in Figs. VII and VIII the cell for golf tees, instead of being separately formed and then introduced and secured in place in the bent sheet, is formed integrally from the sheet itself. The extension 9a is prolonged; it is provided with a third basal crease 19 (of reversed direction of bend) and with a further prolongation 20 with two parallel and transverse creases 21 and 22, and with perforations 23 in the web between the creases 21 and 22, that the whole may be folded and secured by the single staple 11, as shown in Fig. VIII, to form the counterpart of the structure already described. In this instance no reenforcement of corrugated paper is needed within the tee-receiving cell; and in this case, in consequence of the continuity of the web of paper, the lip beneath which the in-bent flap 7 is retained is a folded, two-ply lip.

Figs. VII and VIII illustrate also a provision for the securing of the two parts of the double container that is at once simple, cheaply to be fabricated, and efficient. The sheet 1 is extended along the free edge of one of the panels 5 and 6 in a locking tongue 24; and the other panel is provided with a slot 25. The tongue is bent aside, and in the assembly makes locking engagement with the slot.

The characteristics that make for utility are, first, simplicity—a single web of paper and two

staples may suffice to form the whole; second, rigidity—the folded and stapled article is abundantly strong to endure its brief though perhaps rough term of service; third, compactness—so as to lie snugly in a user's pocket; fourth, the characteristic that it gives direct and immediate advice, which end carries matches, which golf tees; fifth, the supply of tees may be renewed indefinitely; finally, when one of the double compartments is no longer serviceable nor desired, the structure may be torn in two, the undesired half discarded, and the still serviceable half alone retained.

I claim as my invention:

1. A double container for golf tees and matches consisting of a single continuous web of paper and two staples, the web of paper being shaped and bent to constitute two panels integrated along one edge and lying face to face, each panel provided with a pair of end extensions, one of the extensions on one panel being bent and together with a strip of paper matches secured by one of the staples to the panel, and affording a retaining lip for the companion in-bent and cover-forming extension, one of the extensions on the other panel being perforated and bent and secured to its panel by the other staple and forming a cell for the reception of the shanks of golf tees and affording a retaining lip for the companion in-bent and cover-forming extension.

2. The structure of claim 1, the panels being provided with integral interlocking means.

3. A container of the character described comprising two separably connected compartments having backs and at least one covering flap, said container being formed from a single sheet of material folded and weakened on its central longitudinal line and fastened in folded position with the backs of the two compartments in surface contact, so that the weakened line of fold forms a connection between the compartments along one longitudinal edge thereof, and a narrow glued connection between the backs of compartments along the other longitudinal edge thereof.

ANDREW LYLE LINDERMANN.
